UNITED STATES PATENT OFFICE.

HOWARD E. OSKAMP, OF CHICAGO, ILLINOIS.

CORNICE BRACKET.

Application filed April 16, 1927. Serial No. 184,221.

My invention relates to a cornice support and more particularly to a cornice support combined with a curtain rod bracket, and the object of my invention is to provide a device of the above indicated character which is capable of being secured to a window frame for supporting a plurality of curtain rods and for rigidly securing a cornice in place.

10 My invention will be best understood by reference to the accompanying drawing forming a part of this specification and in which,

15 Figure 1 is an elevational view of a cornice support incorporating my invention.

Figure 2 is a top plan view of that disclosed in Figure 1.

20 Figure 3 is a perspective view of my cornice support showing the manner in which the cornice is secured in place thereby.

Figure 4 is an elevational view showing a window frame with a cornice and curtains mounted in position, and showing my invention applied thereto.

25 Figure 5 is a cross-sectional view of the window frame disclosed in Figure 4 and a top plan view of the cornice, the curtain rods and my invention as applied.

For the purpose of illustration and as disclosed in the drawings I have shown the preferred embodiment of my invention in which 10 represents a window frame having my cornice support 11 secured thereto by screws 12 in the usual manner, and having a part of curtain rods 13 and 14 positioned in the holders 15 and 16 which consist of metal stampings and which are secured to the supporting member 17 by suitable rivets 18 and 19. The one end of the supporting member 17 is bent over forming a member 20 adapted to engage the window frame 10. Said member 20 is provided with openings 21 through which the screws 12 are passed for securing the bracket to the window frame as best shown in Figure 5, and a cornice 22 of any suitable composition is shown having a pin 23 secured therein.

The pin 23 is adapted to fit into the curved slot 24 in the upper side of bracket 17 for supporting the cornice and the cornice is provided with a vertical edge 25 adapted to fit snugly against the window frame 10 as

shown. Near the forward end of the bracket 17 is provided a cam member 26 which is pivoted on a rivet 27 and secured by the same to member 17. The cam 26 is provided with a lug 27' by which said cam may be rotated about its axis into the position shown in dotted line in Figure 1 and in which position it locks the pin 23 into the rearward end of slot 24 and as a result it locks the edge or face 25 into engagement with the window frame 10 since the pin 23 is rigidly secured to the cornice 22, by through thread engagement therewith in case the cornice is made of wood, or by being moulded permanently therein in case the cornice is made of plaster of Paris or the like.

For a clear understanding of the application of my device I have shown in Figures 4 and 5 a window frame 10 with curtains 28 and 29 mounted on the rods 13 and 14 respectively and showing the cornice 22 locked into position.

While I have described my invention in its preferred form it is obvious that variations may be made therein without departing from the spirit of my invention and I do not therefore wish to be limited to the precise details of the construction set forth, but desire to avail myself of such variations and modifications as come within the scope of the appended claims.

I claim as my invention:

1. In a curtain rod bracket adapted to be secured to a window frame; notches in the upper side of said bracket adapted to receive a pin secured to a cornice for supporting the same; and eccentric rotatable means 90 for locking said cornice into engagement with said window frame.

2. In a curtain rod bracket adapted to be secured to a window frame; notches in the upper side of said bracket adapted to receive a pin secured to a cornice for supporting the same; a cam for engaging said pin, forcing said cornice into contact with said window frame and for locking said cornice in said position.

3. In a curtain rod bracket adapted to be secured to a window frame; notches in the upper side of said bracket adapted to receive a pin secured to a cornice for support-

ing the same; a cam for engaging said pin, forcing said cornice into contact with said window frame and for locking said cornice in said position; and means on said cam for normally operating the same.

4. In combination, a curtain rod bracket; a window frame; a cornice and a supporting means therefor; a pin-secured-to-said-cornice; means for securing said bracket to

said window frame; means for locking said cornice into engagement with said window frame, comprising a cam having means thereon for manually operating the same into and out of engagement with said pin.

In testimony whereof I have signed my name to this specification.

HOWARD E. OSKAMP.
